UNITED STATES PATENT OFFICE.

DAVID D. LEWIS, OF DETROIT, MICHIGAN.

WINDOW-LATCH.

1,328,284.

Specification of Letters Patent. Patented Jan. 20, 1920.

Application filed October 19, 1916. Serial No. 126,476.

To all whom it may concern:

Be it known that I, DAVID D. LEWIS, a citizen of the United States of America, residing at Detroit, in the county of Wayne 5 and State of Michigan, have invented certain new and useful Improvements in Window-Latches, of which the following is a specification, reference being had therein to the accompanying drawings.

10 This invention relates to a window latch or catch whereby a sash is securely locked when down or is held at any desired elevation by a very simple and efficient and easily operated device.

15 The invention consists in the matters hereinafter set forth, and more particularly pointed out in the appended claims.

In the drawings,

Figure 1 is a view of a window sash on 20 which a device that embodies the invention is mounted together with the window frame or casing and the locking strip secured thereon; and

Fig. 2 is a view, enlarged, partially in section and partially in plan, of a structure and retaining strip.

As herein indicated in preferred form, a corrugated strip 1 of sheet metal or the like 30 is secured to the side of a window frame 2 in such relation to the sash or sash stop that movement of the sash causes the sash side to pass along parallel with and under the strip.

A base plate 22 is secured by suitable 35 means such as screws 33, to the casing, and affords support for a pair of oppositely disposed dogs 3 and 4 which are pivoted on screw studs 5 and 6 so that the end portions 7 and 8 of the pawls may be brought 40 into engagement with the corrugations of the strip 1.

A crescent shaped rock arm 9 of sheet metal has a pair of upturned ends 10 that abut against overlying lateral projections 11 45 and 12 of the pawls 5 and 6. A thumb piece 13 extends from the pivot center of the yoke outwardly beyond the base plate. A screw 14 acts as a pivot for the yoke through 50 which it passes into engagement with the base plate 22.

Preferably the yoke is of sheet metal stamped to proper form and bent to provide the ears or lugs 10 while the finger piece is bent transversely upon itself to form a 55 convenient thumb rest 15.

A crescent shaped spring 16 encircles the

stud 14 with the arms thereof bearing against the margins of the dogs 7 and 8 in such manner as to force the ends thereof to engage the strip unless the manipulation 60 of the yoke holds one of the pawls, as for example the pawl being out of engagement. A casing 17 of suitable design that is detachably secured on the base plate 2 houses the mechanism. 65

As will be understood, the positions of projections 11 and 12 in the path of travel of the projections 10 provide a construction similar to that of a "lost motion" structure, in that each arm or member 9 is capable of 70 movement in one direction without affecting the position of the dog with which its projection 10 co-operates, the movement of the arm in the other direction, however, causing the projection 10 to co-operate with the 75 dog projection to rock the dog on its pivot; the two effects are shown in connection with the positions of the two dogs in Fig. 2 of the drawings.

As will be understood, the normal positions of the parts have the ends of the dogs engaging in a corrugation of strip 1, the projections 10 of member 9 being in contact with projections 11 and 12, the dogs being held in this position by reason of spring 16, 85 and the projections being in contact by reason of the fact that projections 11 and 12 are movable with and form part of the dogs themselves. When, therefore, it is desired to move the sash in either direction the 90 thumb piece 15 is shifted opposite to that in which it is desired to move the sash, thus providing the lost motion effect on the arm which extends in the direction toward which the thumb piece is moved, while the dog in 95 the other position is rocked through the action of the contacting projections, disengaging this latter dog from the corrugation and permitting the sash to be moved in the proper direction, the dog which remains in engagement simply riding over the corrugations which are passed in moving the sash. For instance, in Fig. 2, the parts are in position to move the sash in an upward direction, the lost motion action 100 being present in connection with dog 3 while the positive movement is had in connection with dog 4. The parts will remain in this position as long as pressure is applied to the thumb piece 15; when this pressure is released, the spring tension provided by that 105 portion of the spring 16 which contacts with

dog 4 in Fig. 2, will force said dog toward its normal position, with the result that projection 12 will co-act with projection 10 and rock member 9 on its pivot to 5 a normal position, it being understood, of course, that when both projections 10 are in contact with the projections of the dogs, the tension of spring 16 will be substantially equalized on both dogs, so that member 9 will be maintained in its normal position.

Obviously, changes in the details of construction may be made without departing from the spirit of my invention and I do 15 not care to limit myself to any particular form or arrangement of parts.

What I claim is:—

1. In sash lock construction wherein the sash is normally held locked against movement in either direction and is shiftable in either direction at will, a stationary corrugated strip, a pair of spring supported dogs having independent pivots with the dogs extending in opposite directions from the 25 pivots and each adapted to normally engage strip corrugations, and means for rendering either dog inactive at will, said means including a pivoted member having a pair of arms combinedly producing 30 a crescent-shape element with each arm having a lateral projection, each dog having a projecting element extending into the path of travel of the corresponding arm projection, the respective pivot points and the dog and arm projections being relatively 35 positioned to concurrently permit a lost motion relation with respect to the projection of one dog in the presence of member movement from its normal position to maintain engagement of said dog with the strip 40

and shift the position of the projection of the other dog to disengage said latter dog from the strip, release of operating pressure on the member rendering the disengaged dog active to restore the member to its normal position. 45

2. In sash lock construction, the combination with a corrugated strip adapted to be secured to a window casing adjacent the sash, of a base plate adapted to be secured 50 to the sash adjacent the strip, a pair of pivot studs disposed on the base plate adjacent the corrugated strip, a pair of oppositely disposed dogs each pivoted on a stud and each having an end adapted to engage a 55 recess of the strip, said dogs being operative to lock the sash against movement in the direction of extension of the dog, a yoke pivot stud secured on the base plate, said dog and yoke studs being relatively positioned at points corresponding to the apices of a triangle, a sheet metal crescent shaped yoke pivoted between its ends on the yoke stud, an operating arm extending from the yoke adjacent the yoke studs and having a 60 thumb piece formed on the end portion thereof, lateral projections on each dog, in-turned end portions on the yoke and engaging the projections of the adjacent dog, and a crescent shaped spring secured on the yoke 65 stud with the end portions thereof yieldingly forcing the dogs into engagement with the corrugated strip. 70

In testimony whereof I affix my signature in the presence of two witnesses.

DAVID D. LEWIS.
